Primary Examiner — Kevin K Rudzinski(74) Attorney, Agent, or Firm — Nixon Peabody LLP(57) CLAIM

The ornamental design for a skort, as shown and described.

DESCRIPTION

FIG. 1 is a front elevation view of the skort, shown in a first position of use;

FIG. 2 is a rear elevation view thereof;

FIG. 3 is a right side view thereof;

FIG. 4 is a left side view thereof;

FIG. 5 is a top plan view thereof;

FIG. 6 is a bottom plan view thereof;

FIG. 7 is a front elevation view of the skort of FIG. 1, shown in a second position of use;

FIG. 8 is a rear elevation view thereof;

FIG. 9 is a right side view thereof;

FIG. 10 is a left side view thereof;

FIG. 11 is a top plan view thereof; and,

FIG. 12 is a bottom plan view thereof.

The evenly broken lines (dash-dash lines) shown in the Figures are only for illustrative purposes to show visible environmental structure and form no part of the claimed invention.

1 Claim, 12 Drawing Sheets(56)
